(57) **CLAIM**

The ornamental design for a camera accessory as shown and described.

DESCRIPTION

FIG. 1 is a front view of a camera accessory, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a reference front view showing a state in which the camera accessory is used; and,

FIG. 8 is a reference top, front, left side perspective view showing a state in which the camera accessory is used as an open tripod.

The broken lines depict environmental subject matter of the camera accessory and form no part of the claimed design.

1 Claim, 8 Drawing Sheets
